CLAIM

The ornamental design for an arrhythmia monitor, as shown and described.

DESCRIPTION

FIG. 1 is a rear, bottom, and right-side perspective view of an arrhythmia monitor showing my new design.

FIG. 2 is a rear, bottom, and left-side perspective view of the arrhythmia monitor of FIG. 1.

FIG. 3 is a rear view of the arrhythmia monitor of FIG. 1.

FIG. 4 is a left-side view of the arrhythmia monitor of FIG. 1.

FIG. 5 is a right-side view of the arrhythmia monitor of FIG. 1.

FIG. 6 is a top view of the arrhythmia monitor of FIG. 1; and,

FIG. 7 is a bottom view of the arrhythmia monitor of FIG. 1.

The front view forms no part of the claimed design and is therefore omitted.

The portions of the arrhythmia monitor rendered in short broken lines form no part of the claimed design.
